AUGUST J. WOHLPART, OF NEW YORK, N. Y., ASSIGNOR TO UNION SPECIAL MACHINE COMPANY, OF CHICAGO, ILLINOIS, A CORPORATION OF ILLINOIS

FEEDING MECHANISM FOR SEWING MACHINES

Application filed January 11, 1927. Serial No. 160,432.

The invention relates to new and useful improvements in feeding mechanism for sewing machines, and more particularly to a feeding mechanism having what is commonly referred to as four motions.

An object of the invention is to provide a feeding mechanism of the above type wherein the feed dog is moved back and forth by a member rotating in a circular path about a fixed center, and wherein said feed dog is raised and lowered by a member rotating in a circular path about the same fixed center.

A further object of the invention is to provide a feeding mechanism of the above type wherein the eccentric member for raising and lowering the feed dog is so positioned as to be substantially directly above its connection with the feed bar, which connection with the feed bar partakes of all of the movements of the feed dog.

A still further object of the invention is to provide a feeding mechanism of the above type wherein the means for raising and lowering the feed dog includes a strap or link connected at one end to a part rigidly attached to the feed bar, and connected at its other end to the actuating member rotating in a circular path about a fixed axis.

A still further object of the invention is to provide a feeding mechanism of the above type wherein the feed dog is moved back and forth by a link connected at one end to the feed rocker, and at its other end to the actuating member therefor rotating in a circular path about a fixed center.

These and other objects will in part be obvious and will in part be hereinafter more fully disclosed.

In the drawings which show by way of illustration one embodiment of the invention—

Figure 1 is a longitudinal sectional view through the work support and supporting frame beneath the same, showing the main shaft and a front view of the feed dog actuating mechanism;

Fig. 2 is a view partly in section and partly in end elevation showing the actuating means for the feed rocker;

Fig. 3 is a view partly in section and partly in end elevation showing the disk for adjust-

ably supporting the member which travels in a circular path and oscillates the feed rocker;

Fig. 4 is a sectional view on the line 4—4 of Fig. 2;

Fig. 5 is a sectional view on the line 5—5 of Fig. 1;

Fig. 6 is a view showing the feed dog, the feed bar and the means for moving the feed dog back and forth, with the feed dog at the front end of its stroke;

Fig. 7 is a view similar to Fig. 6, but showing the feed dog at the rear end of its stroke;

Fig. 8 is a view showing more or less diagrammatically the means for raising and lowering the feed dog with the feed dog raised to position for feeding the material;

Fig. 9 is a similar view, but showing the feed dog at the rear end of its stroke;

Fig. 10 is a similar view, but showing the feed dog as having moved beneath the work support and in position to be retracted;

Fig. 11 is a view showing the feed dog as substantially retracted and ready for elevation to its initial starting point for feeding the material, and

Fig. 12 is a diagrammatic view showing the path of travel of the feed dog.

The invention is directed to a feeding mechanism for sewing machines, and more particularly to a feeding mechanism wherein the feed dog is given four motions; that is, it is raised into engagement with the material, then moved for feeding the material, then moved downwardly to release the material, and then returned to its initial position for raising into engagement with the material.

The feed dog is mounted on the feed bar connected to a feed rocker of the usual type. This feed rocker is oscillated by an arm which is rigid with the rocker, and connected at its outer end to a link which in turn is connected to a crank pin carried on the end of the main shaft, and preferably adjustable radially of the shaft. This crank pin travels in a circle about the axis of the shaft as a center. This actuating mechanism for moving the feed dog back and forth, owing to the crank crossing the center line passing through the pivotal connection of the link to the feed rocker and the

center of the shaft, will give a dwell to the feed dog at both ends of its reciprocation. The feed dog is raised and lowered by an eccentric on the main shaft. Cooperating with this eccentric is an eccentric strap which is connected at its lower end to a bracket which is fixed to the feed bar. The point of connection of the eccentric strap with the bracket will partake of all the movements 10 of the feed dog. The eccentric as it rotates, will cause the bracket to be raised and lowered, and this is what imparts the rising and falling movements to the feed dog. The center of the eccentric as it rotates, crosses a line passing through the center of the shaft, and the connection of the eccentric strap to the bracket of the feed bar. This line will shift as the feed dog moves back and forth. The resulting effect on the path of movement 15 of the feed dog is, that the feed dog will move forward to feed the material in a substantially flat or straight path parallel with the work support. As the feed dog reaches the rear end of its stroke, it will quickly 20 move downwardly beneath the work support while the feed dog is substantially idle, and then the feed dog is retracted and brought back to the position for raising the feed dog into engagement with the material. The 25 feed dog is raised into engagement with the material substantially while it is at a dwell at the forward end of its stroke.

Referring more in detail to the drawings, I have shown my improved feeding mechanism as embodied in a sewing machine having a bed 1, with upstanding bearing lugs 2 and 3. Mounted on these bearing lugs is a cloth plate 4 provided with a throat plate 5. The throat plate 5 is in turn provided with feed slots 6. The feed dog 7 is provided in sections which pass up through the feed slots 6.

This feed dog 7 is mounted on a feed bar 8. The feed bar 8 is pivoted at 9 to a feed rocker 10. The feed rocker 10 is pivoted at 11 to the bed 1. The feed rocker 10 is provided with an arm 12 which is rigid therewith, and which extends forwardly from the feed rocker. A main shaft 13 is mounted to 45 rotate in suitable bearings in the supporting lugs 2 and 3. This main shaft carries a disk 14 in its forward end, which is secured thereto by a set screw 15. The disk 14 has a slot 16 extending diametrically across the same. 50 This slot is dove-tailed in cross section, and a block 17 is mounted in the slot. Said block carries a crank pin 18. The block is shifted in the slot by an adjusting screw 19. A link 20 is pivoted at its lower end to the arm 12 of the feed rocker by a pivot bolt 21. This link 20 engages the crank pin 18. On the crank pin is a sleeve 22 which is held thereon by means of a nut 23, and the link 20 engages this sleeve. 55 The feed bar 8 is made in two sections, 8^a

and 8^b. The section 8^a is pivoted to the feed rocker and is provided with a depending portion 8^c which carries a forwardly projecting arm 8^d. This is, in effect, a bracket attached to the main feed bar. The section 8^b is provided with slots 24, 24 and screws 25, 25 passing through said slots, secure the section 8^b to the section 8^a. The purpose of these slots is to permit the section 8^b to be shifted bodily in the direction of the line 75 of feed, and thus the distance between the feed dog and the feed rocker may be varied. This affords an easy way of shifting the working position or path of travel of the feed dog without changing the character or 80 extent of travel. On the main shaft 13 is an eccentric 26. Cooperating with the eccentric 26 is an eccentric strap 27. The eccentric strap 27 is pivoted at 28 to the arm 8^d. The eccentric 26 has a center which moves in a 85 circular path about the center of the main shaft 13.

From Figures 6 and 7, it will be apparent that the crank pin which moves the feed dog back and forth will cross a line passing 90 through the center of the shaft, and the pivotal connection of the link actuated by the crank pin to the feed rocker arm, when the feed dog is at the forward end of its stroke. It will also be apparent that the crank pin 95 will again cross this line passing through the center of the shaft and the pivotal connection of the link to the feed rocker. This occurs when the feed dog is at the rear end of its stroke. When the crank pin is crossing this line referred to, there are practically no movements imparted to the feed rocker; that is, the feed rocker is substantially idle. This occurs when the feed dog is at the ends of its reciprocation. 100

In Figures 8 to 11, the feed dog and the means for raising the same have been shown in various positions, and in Fig. 12, the path of travel of the feed dog has been indicated diagrammatically. When the parts are in the position shown in Fig. 8, the feed dog is at a position indicated at *a* (Fig. 12) in its path of travel. The eccentric 26 is turning in the direction of the arrow in this figure. As the feed dog moves to the position shown 110 in Fig. 9, the eccentric has rotated so as to maintain the feed dog in its raised position during its feed travel. The center of the eccentric is above the center of the shaft during this period, and of course, the center is traveling in a curved path. This would tend to raise the feed dog slightly during its path of travel, but while the feed dog is traveling from the front end to the rear end of its stroke, the pivotal connection 28 between the eccentric strap and the arm carried by the feed bar, also swings in the arc of a circle. The pivotal connection 28 moves from a point 115 at one side of a vertical plane to a point at the other side of a vertical plane, and its path 120

105

110

115

120

125

130

of travel is curved downwardly. This downward curving of the path of travel of the pivotal point 28, offsets the upward curved path of travel of the center of the eccentric, so that 5 the feed bar moves in substantially a straight line during its feeding stroke. When the feed dog is at the rear end of its stroke, it is substantially at a dwell, and during this time the eccentric 26 moves so as to lower the feed 10 dog. This is clearly apparent from Fig. 10 of the drawings. When the feed dog is returned, the center of the eccentric is beneath the center of the main shaft 13, and its downward curved path of travel might be said to 15 be added to the downward curved path of travel of the pivot point 28. During this time, the feed dog is traveling from *b* to *b'* (Fig. 12) in its path. It makes no difference whether this path is a straight line or a curved 20 line in between the points *b* and *b'* (Fig. 12), as the feed dog is idle. When the feed dog is at the front end of its stroke, it is substantially at a dwell, and during this time, the eccentric 26 moves so as to raise the feed dog. 25 The dwell to the feed dog at each end of its stroke is brought about through the crank and link connection to the arm which is rigid with the feed rocker, as has already been pointed out. This particular means for oscillating the feed rocker and imparting feeding 30 movements to the feed dog, together with the particular means described for raising and lowering the feed dog, bring about the travel of the feed dog which is substantially straight 35 during the entire feeding stroke of the dog.

From the above it will be apparent that I have provided a feeding mechanism wherein the feed dog is positively raised and lowered by an eccentric and an eccentric strap. 40 The eccentric is located directly beneath the feed bar, and the eccentric strap is substantially vertical, so that when the feed dog is raised into engagement with the material, it is raised by a direct lift of the eccentric, and 45 when it is lowered, it is lowered by a direct downward pressure on the feed bar. This produces a feeding mechanism wherein the feed dog has a fixed path of travel even though the machine be driven at high speed. 50 It will be further noted from Figs. 8 to 11 inclusive that the shaft rotates in a counterclockwise direction as viewed in these figures, and, therefore, the points of contact between the eccentric and the eccentric strap above 55 the axis of the main shaft are continually moving in a counterclockwise direction. It will also be noted that the eccentric strap during the movements of the feed dog back and forth oscillates about the center of the 60 shaft. The points of contact between the eccentric strap and the actuating eccentric which are located above the axis of the shaft travel first in a clockwise direction and then in a counterclockwise direction as said strap 65 oscillates. Inasmuch as the lower end of the eccentric strap as viewed in Figs. 5 and 8 to 11 inclusive is moving rearwardly during the active feed stroke of the feed bar, the points of contact with the eccentric strap above the center of the shaft are moving in 70 a counterclockwise direction or in the same direction that the points of contact on the eccentric above the center of the shaft are traveling during this portion of the feed stroke. In other words, when the feed dog 75 is raised into contact with the material and is working against the heavy spring pressure of the presser foot it is doing its real work. It lifts the presser foot, holds it lifted so as to lift the fabric off from the throat plate 80 and moves rearwardly carrying the fabric with it. At this time during this heavy wear on the eccentric, the eccentric strap, as noted, at the upper portion is traveling in the same direction as the upper portion of the eccentric, and there is little or no movement between the eccentric strap and the eccentric 85 during this time when there is a heavy lifting strain imposed upon the eccentric. When the feed dog is returning it is free from pressure 90 and then it is that the eccentric strap moves in an opposite direction from the direction of rotation of the eccentric at the upper side of the shaft. By this arrangement of the eccentric strap in conjunction with a shaft 95 rotating as shown and described the wear on the eccentric and eccentric strap is reduced to a minimum. 100 It is obvious that minor changes in the details of construction may be made without departing from the spirit of the invention as set forth in the appended claims.

Having thus described the invention, what I claim as new and desire to secure by Letters-Patent, is—

1. A feeding mechanism for sewing machines comprising a main shaft, a feed bar, a feed dog carried by said feed bar, a feed rocker to which said feed bar is pivoted, means actuated by the main shaft for oscillating said feed rocker, an eccentric on said main shaft for raising and lowering said feed bar, an eccentric strap cooperating with said eccentric, an arm carried by said feed bar and projecting beneath said eccentric to which said eccentric strap is connected, said eccentric strap being disposed so as to move its lower end from one side of a vertical line passing through the center of the shaft to the other side thereof, and means for rotating said main shaft so that the center of the eccentric moves in a direction opposed to the feed when the feed dog is in engagement with the material and moving in the direction of feed to feed the same.
2. A feeding mechanism for sewing machines comprising a main shaft, a feed bar, a feed dog carried by said feed bar, a feed rocker to which said feed bar is pivoted, means actuated by the main shaft for oscillating said feed rocker, an eccentric on said main shaft for raising and lowering said feed bar, an eccentric strap cooperating with said eccentric, an arm carried by said feed bar and projecting beneath said eccentric to which said eccentric strap is connected, said eccentric strap being disposed so as to move its lower end from one side of a vertical line passing through the center of the shaft to the other side thereof, and means for rotating said main shaft so that the center of the eccentric moves in a direction opposed to the feed when the feed dog is in engagement with the material and moving in the direction of feed to feed the same.

lating said feed rocker, an eccentric on said main shaft lying in a vertical plane containing the line of feed, an arm rigidly connected to said feed bar between the feed dog and the rocker and extending beneath said eccentric, an eccentric strap cooperating with said eccentric and connected to the free end of said arm for raising and lowering the feed dog, said connection between the arm and the eccentric strap being movable from a point at one side of a vertical line passing through the center of the shaft to a point at the other side thereof during the feed stroke of the feed dog, and means for rotating said shaft so that the center of the eccentric moves in a direction opposed to the feed when the feed dog is in engagement with the material and moving in the direction of feed to feed the same whereby said feed dog is caused to move in a substantially straight line during the feeding of the material and the bearing points of the eccentric strap on the eccentric are traveling with the eccentric during the feed stroke.

25 In testimony whereof, I affix my signature.

AUGUST J. WOHLPART.
